CLAIM

The ornamental design for a cuttable cordless honeycomb blind as shown and described.

DESCRIPTION

FIG. 1 is a front, right and top perspective view of a cuttable cordless honeycomb blind, showing my design.

FIG. 2 is a rear, left and bottom perspective view thereof.

FIG. 3 is a front elevation view thereof.

FIG. 4 is a rear elevation view thereof.

FIG. 5 is an enlarged left side elevation view thereof.

FIG. 6 is an enlarged right side elevation view thereof.

FIG. 7 is a top plan view thereof.

FIG. 8 is a bottom plan view thereof.

FIG. 9 is an enlarged view of detail 9 in FIG. 1.

FIG. 10 is a cross-sectional view of the cuttable cordless honeycomb blind of FIG. 1, taken along section line 10-10 as depicted in FIG. 3.

FIG. 11 is an exploded view thereof; and,

FIG. 12 is another front, left and top perspective view of the cuttable cordless honeycomb blind in a usable state.

The broken lines shown in the drawings are included for the purpose of illustrating portions of the cuttable cordless honeycomb blind that form no part of the claimed design. The dot-dash broken lines in FIGS. 1 and 9 depict the boundaries of the enlargements and form no part of the claimed design.

The break lines symbolize breaks in the length of the article in which the claimed design is embodied. The appearance of any portion of the article between the break lines forms no part of the claimed design.
